US00D864626S

(12) **United States Design Patent** (10) **Patent No.:** **US D864,626 S**
(45) **Date of Patent:** **** Oct. 29, 2019**

(54) **RETAIL DISPLAY**

(71) Applicant: **June20, Inc.**, Hayward, CA (US)

(72) Inventors: **Paul Chapuis**, Woodside, CA (US);
Steven D. Penny, Oakland, CA (US)

(73) Assignee: **June20, Inc.**, Hayward, CA (US)

(**) Term: **15 Years**

(21) Appl. No.: **29/641,252**

(22) Filed: **Mar. 20, 2018**

(51) LOC (12) Cl. **06-06**

(52) U.S. Cl.

USPC **D6/675**

(58) **Field of Classification Search**

USPC D6/657, 663, 672, 675-675.3, 678, 680.2

CPC A47F 3/007; A47F 5/0043; A47F 5/0081;
A47B 57/00; A47B 57/04
